RAILWAY TRAFFIC CONTROLLING APPARATUS

Filed Aug. 11, 1926

UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 11, 1926. Serial No. 128,595.

My invention relates to railway traffic controlling apparatus, and particularly to apparatus of the type comprising train carried governing means controlled by energy received from the trackway.

In at least one form of railway traffic controlling apparatus which has hitherto been suggested track circuit current is supplied to the rails in series from a point in advance 5 of the train and loop current is supplied to the rails in parallel, and the train is provided with governing means responsive to the track circuit current in advance of the forward axle on the train and to the loop current in rear 10 of such forward axle. One object of the present invention is the provision, in apparatus of this type, of novel and improved means for supplying the track rails with such track circuit and loop currents.

20 I will describe two forms of railway traffic controlling apparatus embodying my invention, and will then point out the novel features thereof in claims.

In the accompanying drawing, Fig. 1 is a 25 diagrammatic view showing one form of railway traffic controlling apparatus embodying my invention. Fig. 2 is a view illustrating a modified form of the apparatus shown in Fig. 1 and also embodying my invention.

Similar reference characters refer to similar parts in both views.

Referring first to Fig. 1, the reference characters 1 and 1^a designate the track rails of a 30 stretch of railway track over which traffic normally moves in the direction indicated by the arrow. These rails are divided by means of insulated joints 2, into a plurality of successive track sections A—B, B—C, etc. Each 35 track section is provided with a source of alternating track circuit current, here shown as a transformer designated by the reference character T with an appropriate distinguishing exponent, and having its secondary 4 connected across the rails adjacent the exit 45 end of the corresponding section through a pole changer P which is controlled by means to be described hereinafter. Interposed between the right-hand terminal of secondary 50 4 of each transformer T and the associated

pole changer P is an impedance 37. The primary 5 of each transformer T is constantly supplied with alternating current from a suitable source such as an alternator M over line wires 3 and 3^a.

55 Each section is further provided with a polarized track relay designated by the reference character R with a distinguishing exponent and having two windings 6 and 7. Winding 6 of each track relay is constantly 60 connected across the rails adjacent the entrance end of the associated section, and winding 7 of each relay R is constantly supplied with alternating current from line wires 3 and 3^a.

65 Each section is provided with a trackway signal designated by the reference character S with an exponent corresponding to the location and capable of indicating proceed, caution or stop. In the form here shown, each 70 signal S is of the semaphore type and is located adjacent the entrance end of the corresponding section. Referring particularly to signal S^b, when relay R^b is energized in the reverse direction so that contact 14—14^b is 75 closed, current is supplied to the caution circuit of signal S^b from line wire 3 and 3^a and the signal indicates caution. When relay R^b is energized in the normal direction, contact 14—14^a is closed and current is supplied to 80 the proceed circuit of the signal from line wires 3 and 3^a so that the signal then indicates proceed. When relay R^b is de-energized, however, both the proceed circuit and the caution circuit for signal S^b are open and the 85 signal then indicates stop.

90 Pole changer P^b is controlled by signal S^b so that when the signal indicates caution or proceed, the pole changer occupies one position in which track circuit current of normal relative polarity is supplied to the rails of section A—B. When signal S^b indicates stop, however, pole changer P^b is reversed and track circuit current of reverse relative polarity is supplied to the rails of section A—B. Each 95 of the remaining pole changers P is controlled by the signal next in advance in the same manner as just described for the control of pole changer P^b by signal S^b. Each signal S also controls a circuit controller des- 100

gnated by the reference character J with an exponent corresponding to the location and arranged to be closed only when the signal indicates caution or proceed.

5 Each track section is also provided with an auxiliary relay designated by the reference character K with a suitable exponent and constantly connected across the rails at an intermediate point in the section. It follows that 10 each relay K is normally energized but that when a train moves through the associated section the relay K for that section becomes de-energized when the train reaches a point somewhat to the left of the point of connection of 15 the relay with the rails.

As shown in the drawing, the section to the right of point C is occupied by a train V , so that relay R^c is deenergized and signal S^c indicates stop. Pole changer P^c is therefore 20 reversed and track circuit current of reverse relative polarity is being supplied to the rails of section $B-C$ from transformer T^c so that relay R^B is energized in the reverse direction and signal S^B indicates caution. Relay K^c is 25 also energized. Current of normal relative polarity is supplied to the rails of section $A-B$ from transformer T^B and relay R^A is energized in the normal direction so that signal S^A indicates proceed. In similar manner 30 the section to the left of point A is supplied with track circuit current of normal relative polarity.

The section to the left of point A is occupied by a train indicated diagrammatically 35 at V^a , which train is provided with a track receiver H and a loop receiver L . The track receiver H comprises two magnetizable cores 24 and 24^a carried on the train in advance of the forward axle 23 and located in inductive 40 relation with the two track rails 1 and 1^a respectively. Core 24 is provided with a winding 25 and core 24^a is provided with a similar winding 25^a , windings 25 and 25^a being connected in series in such manner that the voltages induced therein by alternating currents 45 flowing in opposite directions in the two track rails at an instant are additive. The windings of the receiver H are connected through an amplifier 26 with one winding 27 of a train 50 carried relay D . The loop receiver L comprises two cores 28 and 28^a located in inductive relation with the two track rails 1 and 1^a respectively in rear of the forward axle 55 of the train. In actual practice the loop receiver is usually placed between the locomotive and tender. Two windings 29 and 29^a located on cores 28 and 28^a respectively are connected in series in such manner that the voltages induced therein by alternating currents 60 which flow in the same direction in the track rails at an instant are additive. The windings of receiver L are connected through an amplifier 30 with a second winding 31 of relay D .

65 When train V^a enters section $A-B$, track

circuit current from transformer T^B flows from the left-hand terminal of secondary 4 of this transformer through pole changer P^B and rail 1^a of section $A-B$ to the forward axles of the train and thence by rail 1, back through the pole changer P^B and impedance 37 to the right-hand terminal of secondary 4 of transformer T^B . The presence of the train in section $A-B$ de-energizes relay R^A , and current from transformer T^B also flows from the left-hand terminal of secondary 4 of this transformer, through pole changer P^B and rail 1^a to the forward axles of the train, where the current divides, part flowing through rail 1 and part through rail 1^a to reactance 8 at the 70 entrance end of the section and thence over wire 19, back contact 9 of the track relay R^A , wire 20, impedance 10, and front contact 11 of relay K^B to the right-hand terminal of secondary 4 of transformer T^B . When this circuit is closed, the electromotive force of secondary 4 of transformer T^B causes loop current to flow therethrough. It follows that the rails under receiver H are then supplied with alternating track circuit current 75 which flows in opposite directions in the two rails, and that the rails under receiver L are supplied with alternating loop current which flows in the same direction in the two rails. Relay D is therefore energized. When the track circuit current supplied to the train is of normal relative polarity contact 80 85 90 95 100 105 110 115 120 125 130 135 140 145 150 155 160 165 170 175 180 185 190 195 200 205 210 215 board the train. Should the train attempt to enter the occupied section to the right of point C, the receiver H will be deprived of track circuit current by the wheels and axles 5 of train V and relay D will continue to be de-energized, so lamp 36 will remain lighted to give a stop indication on board the train.

Referring now to the modified form of apparatus shown in Fig. 2, the alternating current track relays have been replaced with polarized direct current relays also bearing the reference characters R. Current for controlling these relays is supplied to the rails of each section by a track battery designated 10 by the reference character G with a suitable exponent, which battery is interposed between secondary 4 of transformer T and a rail of the section. In place of the reactance 15 of Fig. 1, a resistor 8^a is connected across the 20 rails adjacent the entrance end of each section. A resistor is necessary in Fig. 2 to prevent shunting of the adjacent track relay. The circuits for the signal S will be apparent 25 from the inspection of the drawing, these circuits being supplied with current from terminals *a* and *b* of a suitable source of energy not shown in the drawing. The operation of 30 the apparatus will be readily understood from the explanation of Fig. 1, the only differences being that the track relays R and the auxiliary relays K are responsive to direct current instead of alternating current and are energized by current from battery G instead of by current from transformer T. Alternating track circuit current and alternating 35 loop current are supplied to the rails of each section for the purpose of controlling the governing means on board the train by transformer T for each section in exactly the 40 same manner as in Fig. 1.

Although I have herein shown and described only two forms of railway traffic controlling apparatus embodying my invention, it is understood that various changes and 45 modifications may be made therein within the scope of the appended claims without departing from the spirit and scope of my invention.

Having thus described my invention, what 50 I claim is:

1. In combination, a stretch of railway track, a transformer the primary of which is connected with a source of alternating electromotive force, means for reversibly connecting the secondary of said transformer across the rails adjacent one end of the stretch, an impedance interposed between one terminal of said secondary and the rails of the stretch, and means for connecting such one 55 terminal of the secondary with both rails adjacent the opposite end of the stretch.

2. In combination, a stretch of railway track, a transformer the primary of which is connected with a source of alternating electromotive force, means for reversibly con-

necting the secondary of said transformer across the rails adjacent the exit end of the stretch, an impedance interposed between one terminal of said secondary and the rails of the stretch, and means for connecting such 70 one terminal of the secondary with both rails adjacent the entrance end of the stretch.

3. In combination, a stretch of railway track, a source of alternating electromotive force, means for reversibly connecting the 75 source across the rails adjacent the exit end of the stretch, an impedance interposed between one terminal of said source and a rail of the stretch, a relay connected across the rails at an intermediate point in the stretch, 80 means controlled by said relay for at times connecting said one terminal of the source with both rails adjacent the entrance end of the stretch, and train carried governing means controlled by energy in the track rails. 85

4. In combination, a stretch of railway track, a source of alternating electromotive force, means for reversibly connecting the source across the rails adjacent the exit end of the stretch, an impedance interposed between one terminal of said source and a rail of the stretch, a relay connected across the rails at an intermediate point in the stretch, a second impedance connected across the rails adjacent the entrance end of the stretch, means 90 including a front contact of the relay for at times connecting the mid-point of said second impedance with said one terminal of the source, and train carried governing means responsive to currents in the track rails in front 100 of and in rear of the forward axles of the train.

5. In combination, a stretch of railway track, a source of alternating electromotive force, means for reversibly connecting the 105 source across the rails adjacent the exit end of the stretch, an impedance interposed between one terminal of said source and a rail of the stretch, means responsive to traffic conditions in advance of such stretch for at times connecting such one terminal of the source with both rails adjacent the entrance end of the stretch, and train carried governing means controlled by alternating currents in the 110 track rails in advance of the train and in rear of the forward axles of the train.

6. In combination with a stretch of track occupied by a train, a source of alternating electromotive force; a first circuit including 120 said source, a forward axle of the train and the rails of the stretch in series ahead of the train; a second circuit including said source, one rail of the stretch ahead of the train, a forward axle of the train, and the rails of the stretch in parallel in rear of the train, and governing means on the train responsive to currents in said two circuits.

7. In combination, a stretch of railway track, a source of alternating track circuit current connected across the rails adjacent 130

one end of the stretch, an impedance interposed between one terminal of the source and a rail of the stretch; a track relay connected across the rails adjacent the other end of the stretch and responsive to current from said source, means controlled by said track relay for at times connecting said one terminal of

the source with both rails adjacent such opposite end of the stretch, and governing means on a train controlled by current supplied to the rails from such source. ¹⁰

In testimony whereof I affix my signature.

HOWARD A. THOMPSON.
